SET OF CANDLE HOLDERS

Charles Fischett, South Ozone Park, N. Y.

Application February 18, 1955, Serial No. 34,576

Term of patent 14 years

(Cl. D48—2)

Fig. 1 is a perspective view showing two members of the set of candle holders in ornamental use;

Fig. 2 is a top plan view of the said member shown in Fig. 3;

Fig. 3 is a front elevation thereof, and Fig. 4 is a side elevation thereof.

Figs. 5-12 inclusive are front elevations of the remaining members of the set of candle holders, and all the figures aforesaid show my new design for such set of candle holders.

The broken lines shown in Fig. 1 are for illustrative purposes only.

I claim:

The ornamental design for a set of candle holders, substantially as shown and described.
